(57) **CLAIM**

The ornamental design for a handle for USB connectors and flash drives, as shown and described.

DESCRIPTION

FIG. 1 is a top, front and right side perspective view of a handle for USB connectors and flash drives showing our new design;

FIG. 2 is a bottom, rear, and left side perspective view thereof;

FIG. 3 is a front elevation view thereof;

FIG. 4 is a right side elevation view thereof;

FIG. 5 is a rear elevation view thereof;

FIG. 6 is a left side elevation view thereof;

FIG. 7 is a top plan view thereof; and,

FIG. 8 is a bottom plan view thereof.

The features shown in broken lines depict environmental subject matter only and form no part of the claimed design.
